UNITED STATES PATENT OFFICE.

GEORGE R. DODD, OF ANDERSON, SOUTH CAROLINA, ASSIGNOR OF ONE-THIRD TO THOMAS GLENN, OF ABBEVILLE, SOUTH CAROLINA.

CAR-REPLACER.

SPECIFICATION forming part of Letters Patent No. 683,684, dated October 1, 1901.

Application filed July 23, 1901. Serial No. 69,440. (No model.)

To all whom it may concern:

Be it known that I, GEORGE R. DODD, a citizen of the United States, residing at Anderson, in the county of Anderson and State of South Carolina, have invented a new and useful Car-Replacer, of which the following is a specification.

The invention relates to improvements in car-replacers.

10 The object of the present invention is to improve the construction of car-replacers and to provide a simple and comparatively inexpensive device of great strength and durability adapted to be readily applied to a rail 15 for replacing the wheels of a car or locomotive and capable of being rigidly held at the desired adjustment.

The invention consists in the construction and novel combination and arrangement of 20 parts hereinafter fully described, illustrated in the accompanying drawings, and pointed out in the claims hereto appended.

In the drawings, Figure 1 is a side elevation of a car-replacer constructed in accordance with this invention. Fig. 2 is a plan view of the same. Figs. 3 and 4 are detail views of the clamp. Fig. 5 is a detail view of the supporting-plate. Fig. 6 is a detail sectional view illustrating the manner of securing the clamp to a rail. Fig. 7 is a detail view of the outer end of the main pivoted bar. Fig. 8 is a detail view of the supplemental short pivoted bar.

Like numerals of reference designate corresponding parts in all the figures of the drawings.

1 designates a clamp designed to be arranged at one side of a rail and to be supported upon a cross-tie 2, as clearly illustrated in Figs. 1 and 2 of the accompanying drawings, and provided with depending ears 3, receiving the shanks of hook-bolts 4, which extend beneath the rail and engage the bottom flange thereof at the opposite side of the same. The 45 hook-bolts are provided at their outer ends with nuts 5, and the clamp is provided at its center with a perforation 6 for the reception of a vertical pivot 7 for connecting an inclined guide-bar 8 to the clamp, which forms 50 a support for the upper end of the guide-bar. The inclined guide-bar, which is detachably

pivoted to the supporting-clamp, is adapted to be arranged at an angle to the rail 9 for guiding the wheel of a car or locomotive back upon the rail when the said wheel has left 55 the track. The clamp and the pivoted guide-bar may be constructed of any suitable metal, and the lower end of the guide-bar is adapted to be arranged upon a supporting-plate 10, as shown in full lines in Fig. 2 of the drawings, or upon the adjacent cross-tie, as illustrated in dotted lines in Fig. 2. The pivoted guide-bar is provided at the lower face of its lower end with a pair of depending spurs or 60 projections 11, adapted to embed themselves 65 in the cross-tie to prevent the guide-bar from slipping. When the lower or outer end of the pivoted guide-bar is located beyond the adjacent cross-tie, it is supported by the rectangular plate 10, which forms a broad base 70 and which prevents the car-replacer from sinking into the ground. The supporting-plate 10 is provided at its center with a clip 13, having L-shaped flanges 14 for engaging 75 grooves 15 of the sides of the lower or outer end of the guide-bar. The grooves extend inward from the end of the guide-bar, and the flanges 14 are readily engaged with the same, whereby the guide-bar is securely interlocked with the supporting-plate. The 80 clip-plate, which may be mounted on the supporting-plate in any suitable manner, is provided with sockets or depressions 16 to receive the spurs, whereby the latter are prevented from being injured. The grooves are 85 of sufficient width to permit the spurs or projections to be readily engaged with and disengaged from the clip. Instead of providing a separate clip-plate the flanges 14 may be constructed in any other suitable manner. 90

In order to prevent the pivoted guide-bar from slipping outward under the lateral pressure incident to replacing a wheel upon the rail when the supporting-plate is used, the latter is connected with the rail by a chain 95 17, secured at one end to the supporting-plate and provided at its other end with a hook 18 for engaging the bottom flange of the rail. The chain extends beneath the rail, and the supporting-plate is provided with a 100 perforation or opening 19, through which passes the chain. The chain extends upward

through the opening 19 from the bottom of the supporting-plate, which is designed to be grooved or hollowed out at its lower face adjacent to the opening 19 to receive the chain 17. The chain may be secured to the supporting-plate by a pin or key 21, and it may be shortened by engaging the pin or key with any one of the intermediate links of the chain; but any other suitable means may be employed for attaching the chain to the supporting-plate and for varying its length. The lower end of the pivoted guide-bar is beveled or rounded, and the wheel of a car or locomotive is adapted to ride up the said 15 guide-bar, and it will be directed by the same to the rail. The clamp is also adapted to receive a short guide-bar 22, adapted to be employed when the derailed wheel is close to the rail. This short guide-bar, which is secured 20 to the supporting-clamp by the pivots 7, is of a length to extend to the next cross-tie, and it is provided at its lower end with spurs or projections for engaging the same to prevent it from slipping laterally. The pivot may be 25 of any desired construction, and it may consist of a bolt or any other suitable device.

It will be seen that the car-replacer is exceedingly simple and inexpensive in construction, that it possesses great strength and 30 durability, and that it is adapted to be arranged at different angles to a rail to suit the position of a derailed wheel. It will also be apparent that the pivoted guide-bar may be either supported upon a cross-tie or upon the 35 ground at a point beyond the cross-tie and that when supported in the latter position it is prevented from sinking into the ground.

What I claim is—

1. A car-replacer comprising a pivoted 40 guide-bar having an inclined upper face and adapted to be arranged at different angles to a rail, a clamp supporting the inner end of

the guide-bar and arranged to engage the rail, a supporting-plate designed to be located beyond the cross-ties and adapted to be placed 45 at different distances from the rail and receiving the outer end of the guide-bar, and an adjustable connection extending from the supporting-plate to the rail and adapted to be lengthened and shortened, substantially 50 as and for the purpose described.

2. A car-replacer comprising a pivoted guide-bar, adapted to have its outer end supported upon one of the cross-ties or to be arranged beyond the same, a supporting-plate 55 designed to be arranged beyond the cross-ties to support the outer end of the guide-bar, and detachably interlocked with the same to enable it to be removed when the guide-bar is supported by a cross-tie, and means for adjustably connecting the supporting-plate with a rail, substantially as described.

3. A car-replacer comprising a pivoted guide-bar designed to be arranged at an angle to a rail and provided at its outer end with 65 opposite grooves, and a supporting-plate provided with flanges engaging the said grooves, substantially as described.

4. A car-replacer comprising a pivoted guide-bar provided at its outer end with spurs 70, and having grooves at its sides, a supporting-plate having a clip provided with flanges for engaging the grooves and having sockets to receive the spurs, and a chain for connecting the supporting-plate with a rail, substantially 75 as described.

In testimony that I claim the foregoing as my own I have hereto affixed my signature in the presence of two witnesses.

GEORGE R. DODD.
